UNITED STATES PATENT OFFICE.

FREDERICK G. FISCHER, OF NEW HAVEN, CONNECTICUT.

FOLDING BOX.

953,132.

Specification of Letters Patent. Patented Mar. 29, 1910.

Application filed June 23, 1908 Serial No. 503,821.

To all whom it may concern:

Be it known that I, FREDERICK G. FISCHER, a citizen of the United States, and a resident of New Haven, in the county of New Haven and State of Connecticut, have invented a new and Improved Folding Box, of which the following is a full, clear, and exact description.

The principal objects which the present invention has in view are: to provide a folding box having an inner compartment so constructed that dampness is excluded from the box; to provide a folding box the outer wall of which is so constructed as to form no visible joint; to provide a construction wherein both the inner and outer walls of the box are provided with view openings which align; and to provide a construction having a hinged cover having the four structural sides firmly secured to form a rigid structure.

One embodiment of the present invention is disclosed in the construction illustrated in the accompanying drawings, in which similar characters of reference indicate corresponding parts in all the views.

Figure 1 is a perspective view of a box constructed in accordance with the present invention; Fig. 2 is a perspective view of the inner wall; Fig. 3 is a vertical longitudinal section of a box constructed in conformity with this invention; Fig. 4 is a vertical cross section of the inner wall; Fig. 5 is a horizontal section of the outer wall of the box, showing the arrangement and construction of the bottom flaps; Fig. 6 is a plan view from beneath, showing the construction and arrangement of the bottom flaps of the outer wall; Fig. 7 is an outspread view of the blank forming the outer wall of the box; Fig. 8 is an outspread view of the blank forming the inner wall of the box; Fig. 9 is a top view of the inner wall shown in the act of being folded; Fig. 10 is a vertical longitudinal section of the structure forming the outer wall of the box; Fig. 11 is a perspective view of the outer wall of the box shown in a modified form; and Fig. 12 is an outspread view of the blank from which the modified form of the outer wall is constructed.

The box, which this construction is most adapted to form, is intended to be used for holding crackers or other substances, wherein it is desired to expose the same to view and wherein it is thought essential to exclude

from the contents of the box any dampness which might rise upward from the shelf.

A further essential to this form of box is that the sides should present an unbroken 60 surface to receive any form of pictorial design or configuration.

It therefore becomes essential that the construction of the inner and outer walls shall differ, to embody the two essentials set 65 forth.

A further desirable feature incident to such construction is that the cover or lid shall be hinged to the body structure and have depending side walls. 70

It is in recognition of the necessities above stated that I have provided a construction, herein shown and described, having two separate walls formed from blanks separately constructed and essentially differing. 75

For the convenience of description I will first describe the inner wall which is illustrated at Fig. 8 of the drawings.

As above stated, it is essential to the proper construction of the inner wall that 80 there shall be no opening or joint which would lead, through capillary or other action, the moisture from the bench or floor on which the box may be set, up to and within the containing portion of the box. In Fig. 85 8 of the drawings the scoring of the blank is illustrated by dotted lines shown in the said figure, the full lines illustrating severed or cut portions. The scores form the bottom panel 14, from the four sides of which are 90 extended the panels 15, 16 and 17, 18. The diagonal scores 18, 18 are extended from the corners of the bottom panel 14 to the inner corners of the folding extensions 20, 20. Upon the scores 18, 18 the extensions 20, 20 95 fold together, as shown in Fig. 9 of the drawings. In thus folding the extensions 20, 20 upon each other and along the scores 18, 18, the panels 15, 16 and 17, 18 are bent upward from the bottom 14. The folded extensions 20, 20 are extended outward, from the lower corner upward, and the folded extensions are then led around, upon and to the outside of the panels 17, 18 and there secured. 100 105

The folded form above described is secured by means of the tabs 21, 21 and the sockets 22, 22, so disposed on opposite sides as to receive the tabs 21, 21. The sockets 22, 22 are formed substantially as shown 110 in the drawings and of slightly less length than the length of the head of the tabs 21, 21.

The tabs 21, 21 are mounted upon extensions 23, 23, protruded from the extensions 20, 20 on the one side of the blank forming the inner wall. The extensions 23, 23 are of sufficient length to overlap the extensions 20, 20 on the opposite side of the blank to permit the tabs 21, 21 to enter and engage the sockets 22, 22. When the side walls of the box are thus held in their vertical position by reason of the engagement of the tabs 21, 21 with the sockets 22, 22, the structure of the inner wall of the box is further strengthened by tabs 24, 24 on extensions 25, 25, to be inserted within sockets 26, 26 formed in the extensions 20, 20.

It will be noticed that with the turning of the extensions 25, 25 down upon the folded extensions 20, 20 the passage between the folded extensions and the panels 17, 17 on the outside thereof is closed by the said extensions 25, 25. This construction is such that should any water gain admission through the outer wall of this box and be carried by capillary action upward between the walls of the extensions 20, 20 and the panels 17, it would be prevented from entering the box through this passage by the folded extensions 25, 25. A further purpose is served by the extensions 25, 25 in strengthening the anchorage of the various parts.

With the construction above described, it will be seen that we have a containing vessel to which the access of dampness from the outside except through the open top is completely prevented. At the same time, it will be seen that the sides are not such as would be desired for a display box or carton.

The display feature in the completed box is provided by the outer wall, formed from the blank as shown in Fig. 7 of the drawings. In this blank the panels 26, 27, 28 and 29 form the vertical sides of the completed box. In this view of Fig. 7 as in Fig. 8, the dotted lines illustrate the scores or deep rulings upon which the material is bent.

The bottom of the box is formed by panels 30, 31, 32 and 33. These panels are separated from the adjacent panels by severing cuts, as shown by the full lines separating them. They are folded at right angles to the side forming the panel to which they are connected. They overlap from opposite directions when the panels 26, 27, 28 and 29 are formed to a rectilinear shape. In this position of the side panels the tabs 34, 34 of the panel 32 are brought into position, to be inserted within sockets 35, 35 formed in the panel 30, and the tabs 34 of the panel 31 are inserted within the sockets 35 formed in the panel 33. The bottom thus formed for the outer wall is a strong structure, consisting in the major part of four thicknesses, as shown in Figs. 5 and 6.

To prevent the vertical meeting edge of the panel 29 separating from the panel 26, the latter is provided with a lateral extension 36, which when bent at right angles to the panel 26 is glued, stapled or sewed to the panel 29. When thus folded and secured together, the panels 26, 27, 28 and 29 form a substantial and rigid box like structure. This structure is slightly larger than the structure formed from the blank illustrated in Fig. 8 of the drawings, as it is intended that the inner wall formed from the blank shown in Fig. 8 shall be inserted within the outer wall formed by the blank shown in Fig. 7. The difference in size is slight, to require some little pressure to force the one within the other.

Where the completed box is to be used to contain articles it is desired to display, both the blank forming the inner wall and the blank forming the outer wall are cut to form an opening 37, 37. These openings align when the two formed structures are forced together, as above set forth. The inner wall is provided while in the blank with a sheet of isinglass, mica or other material 38. This is glued or otherwise secured to said wall. The covering for the opening 37 in the inner wall is preferably secured to the outside of the said wall.

The completed box is provided with a hinged cover formed by a panel 39 which is attached to the panel 29 substantially as shown in Fig. 7 of the drawings. From each of the sides of the panel 39 are extended flaps 40 and 41, 41. All of the flaps are of the same width. Those designated as 41, 41 are bent from the panel, to overlap the completed box and are provided with sockets 42, 42, shaped substantially as shown in said Fig. 7 of the drawings. The flaps 40, 40 are provided with end extensions 43, 43, on which are formed tabs 44, 44, adapted to extend within and engage the sockets 42. When the flaps 40, 40 and 41, 41 are bent from the panel 39 and secured by the tabs 44, 44 engaging with the sockets 42, 42, a cover is formed for the box which resembles in structure and operation the hinged covers of metal and wooden boxes. The hinge is formed by the scoring interposed between the panel 29 and the adjacent flap 40.

It will be noticed that the scoring which separates the panel 29 from the flap 40 interposed between the said panel 29 and the said panel 39 is disposed below the upper edge of the box structure formed by the blank shown in Fig. 7 of the drawings. The scoring just referred to is at the same level on the completed box structure as will be the turned edges of the other of the flaps 40, 41, 41, when the top or lid is turned down upon the box structure, so as to infold the upper edge thereof.

In the modified form of the box structure

shown at Figs. 11 and 12 of the drawings; the upper edge of the panels 26, 27 and 28 are formed level with the scoring constituting this hinge, as above described. In this form of the construction the inner wall shown in dotted lines at Fig. 11 constitutes the guides for the top or cover.

In the form of box illustrated at Fig. 1 of the drawings, the upper edge down to the dotted line therein shown forms the guide for the cover, while extensions 45, 45 form lateral inward extensions or covering edges for the box structure, sealing the many ply formation of the side walls. In the completed box structure, if desired, the extensions 45, 45 may be held in their butted relation by any suitable form of construction.

In the modified form shown at Figs. 11 and 12, I have changed the construction of the top or lid by forming in the blank the corner sections 46, 46. These sections I fold inward on the line 47, 47 then turn the folded sections against the extensions 41, 41 and secure them in this position by driving metal staples 48, 48 through the assembled layers.

Having thus described my invention, I claim as new and desire to secure by Letters Patent:

1. A folding box comprising a plurality of box-like receptacles adapted to fit the one within the other to form the inner and outer walls of the said box, constructed each from a continuous flat spread sheet adapted to be folded in receptacle form with the lapped portions of the inner receptacle disposed on the exterior of the side sections thereof, and the lapped portions of the outer receptacle disposed on the bottom section thereof, the said outer receptacle being provided with flat extensions to over-fold the upper edge of the inner receptacle; and means for securing the said lapped portions in folded position.

2. A folding box, comprising an inner box-like receptacle formed from a continuous sheet folded to form inner bottom and side flush surfaces; an outer box-like receptacle formed from a continuous sheet folded to form outer side flush surfaces and having a bottom consisting of a plurality of lapped extensions of the sides of said outer receptacle; and securing means for holding the said receptacles together to form a single structure having flush inner and outer surfaces.

3. A folding box comprising a plurality of box-like receptacles adapted to fit the one within the other to form the inner and outer walls of the said box; said receptacle forming the inner wall embodying a continuous sheet bended to form a rectangular inner space the lateral extensions whereof are upturned to form the sides of said receptacle and the material intermediate the said sides whereof is unsevered and folded outward

and lapped upon the said sides of the receptacle; the said outer receptacle formed from a continuous sheet bended to form rectangular sections having extensions adapted to fold each upon the other to form a bottom 70 for said receptacle; and securing means for holding the said receptacles together to form a single structure having an impenetrable inner wall and flush inner and outer surfaces.

4. A folding box comprising a plurality of box-like receptacles adapted to fit the one within the other to form the inner and outer walls of the said box; said receptacle forming the inner wall embodying a continuous 80 sheet bended to form a rectangular inner space the lateral extensions whereof are upturned to form the sides of said receptacle and the material intermediate the said sides whereof is unsevered and folded outward 85 and lapped upon the said sides of the receptacle; the said outer receptacle formed from a continuous sheet bended to form rectangular sections having extensions adapted to fold each upon the other to form a bottom 90 for said receptacle; and securing means embodying a flap extension of the side sections of the outer receptacle to over-fold the upper edge of the inner receptacle to hold the said receptacles together to form a single 95 structure the inner wall whereof is impenetrable and having flush inner and outer surfaces.

5. A folding box comprising an inner box-like receptacle formed from a continuous sheet folded to form inner bottom and side flush surfaces; an outer box-like receptacle formed from a continuous sheet folded to form outer side flush surfaces and having a bottom consisting of a plurality of lapped 100 extensions of the sides of said outer receptacle and a lateral extension to one of said sides to form a top for said folding box, said lateral extension having flaps adapted to be bent from said top to form guides therefor, 105 said top being flexibly connected with said side sections; and securing means for holding the said receptacles together to form a single structure having flush inner and outer surfaces.

6. A folding box comprising a plurality of box-like receptacles adapted to fit the one within the other to form the inner and outer walls of said box; the said receptacle forming the inner wall constructed from a continuous sheet folded to form inner bottom and side flush surfaces; the said receptacle forming the outer wall formed from a continuous sheet folded to form box side sections disposed in serial order each of said sections having a flap-like extension adapted to be folded upon each other to form the bottom of the receptacle; a box top adapted to infold the upper edge of said inner receptacle consisting in a lateral extension of 110 115 120 125 130

one of said side sections having extended from the sides thereof depended guides, one of said guides being flexibly attached to the side section to which said top is attached to form a hinge for said top; and securing means for holding the said receptacles in their box-like form.

7. A folding box comprising a plurality of box-like receptacles adapted to fit the one within the other to form the inner and outer walls of said box; the said receptacle forming the inner wall constructed from a continuous sheet folded to form inner bottom and side flush surfaces; the said receptacle forming the outer wall formed from a continuous sheet folded to form box-like sections disposed in serial order, each of said sections having a flap-like extension adapted to be folded upon the others to form the

bottom of the receptacles; a box top adapted to infold the upper edges of said receptacles consisting in a lateral extension of one of said side sections having extended from the sides thereof depended guides, one of said guides being flexibly attached to the side section to which said top is attached and below the upper edge of the other of said side sections to form a hinge for said top; and securing means for holding all of said parts in their folded position.

In testimony whereof I have signed my name to this specification in the presence of two subscribing witnesses.

FREDERICK G. FISCHER.
